Term of patent 14 years

(Cl. D61—1)

FIG. 1

FIG. 2

FIG. 3

FIG. 4

FIG. 5

FIG. 6

FIG. 1 is a front perspective view of a film processor showing my new design.

FIG. 2 is an elevational view taken from the left side thereof.

FIG. 3 is an elevational view taken from the right side thereof.

FIG. 4 is a top plan view thereof.

FIG. 5 is a front elevational view thereof.

FIG. 6 is a rear elevational view thereof.

The dominant features of my design reside in the portions shown in full lines, it being understood that the broken line representation of the support legs shown in FIGS. 1, 2, 3, 5 and 6 is for purposes of illustration only.

I claim:

The ornamental design for a film processor, as shown and described.
